CLAIM

The ornamental design for a liquid level gauge, as shown and described.

DESCRIPTION

FIG. 1 is a perspective view of the liquid level gauge; FIG. 2 is a front view thereof; FIG. 3 is a right side view thereof; FIG. 4 is a back view thereof; FIG. 5 is a left side view thereof; FIG. 6 is a top view thereof; FIG. 7 is a bottom view thereof; and, FIG. 8 is an enlarged partial perspective view showing the dial portion exploded from the head portion. The particular angular position of the pivotable float arm with respect to the support arm in the above drawing figures is for illustrative purposes only and forms no part of the claimed design.
